UNITED STATES PATENT OFFICE.

HENRY C. MAUL, OF DETROIT, MICHIGAN, ASSIGNOR TO THE MICHIGAN STOVE COMPANY, OF DETROIT, MICHIGAN, A CORPORATION OF MICHIGAN.

COMBINED COAL AND GAS RANGE.

1,306,269.

Specification of Letters Patent. Patented June 10, 1919.

Application filed January 21, 1918. Serial No. 212,886.

To all whom it may concern:

Be it known that I, HENRY C. MAUL, a citizen of the United States of America, residing at Detroit, in the county of Wayne and State of Michigan, have invented certain new and useful Improvements in Combined Coal and Gas Ranges, of which the following is a specification, reference being had therein to the accompanying drawings.

10 In combining coal and gas ranges, stove manufacturers have found it difficult to satisfactorily eliminate certain objectionable results, which may have heretofore been considered features of a good stove. For instance, in a combined coal and gas range, with the gas burner located below or even above the bottom of the oven, it is practically impossible to prepare food by having the utensils rest upon the bottom of the 15 oven. As an example of such stove, there may be cited my combination coal and gas range disclosed in Patent No. 1,154,038, granted Sept. 21, 1915. This particular stove has the gas burner extending through 20 and above the bottom wall of the oven necessitating the placing of a platform or rest member above the burner for cooking utensils. It will also be noted that the bottom 25 of the oven is interrupted in order to provide proper ventilation for the burner and in consequence of this construction considerable space is lost. As far as I am aware, all 30 combination coal and gas ranges are defective about the oven bottom by either having an auxiliary oven bottom, as a rest member or an oven bottom too hot to accommodate 35 cooking utensils.

Then again, such a stove necessitates a multiplicity of flues and passages, together 40 with controlling valves and dampers, so that the stove may be independently operated with either coal or gas as a fuel. A multiplicity of valve or damper adjustments will soon dishearten or discourage a cook, particularly if in any manner careless, with the 45 result that coal and gas ranges will be comparatively maintained units.

So, with these and other defects in view, I have devised a combination coal and gas 50 range which may be characterized in the following particulars.

First, there is an oven with a flue or passage beneath the same and the gas burner employed for heating the oven is located in

proximity to the oven bottom, but not so 55 close thereto as to overheat the bottom and prevent cooking utensils from being placed thereon. In other words, the gas burner is disposed so that the oven bottom will be properly heated and also the walls of the 60 oven with a proper circulation of heat throughout the interior of the oven to insure uniform cooking therein.

Second, a novel damper or valvular member is located in proximity to the gas burner 65 of the stove so that under gas operation the burner may receive sufficient air for proper combustion and also have its heating units pass under the oven to heat the bottom thereof. This damper or valvular member is adjustable so that the gas heated oven of the 70 stove may be readily converted into a coal heated oven.

Third, the disposal or arrangement of the flues is an important item, so that a minimum flue area will permit of the stove being used either as a coal or gas operated stove of minimum size. In the stove as now constructed and used I am able to use certain flues for either coal or gas operation by simply employing a flue deflector or adjustable member that will permit of products of combustion of coal or gas, being properly circulated to insure a thorough heating of the oven and proper ventilation for the flames 85 maintained either by the gas or coal.

Fourth, there are certain communications or operative relations which must be established between an oven and flues either by coal or gas as a fuel, so that the oven will be 90 properly ventilated to insure proper cooking and that there will be no danger of flame suffocation and poor drafts, and it is with this end in view that the flue controlling means of the stove includes means for 95 proper ventilation of the oven when gas or coal heated.

Fifth, by a member, adjustable at will, I may by a single operation control the use of the stove either by coal or gas as a fuel, 100 that is, by adjusting a single member I regulate the gas when in use, provide for the burner ventilation, provide for the oven ventilation and the gas operation, and place in use certain flues for either gas or coal operation by adjusting a dual deflector. In somuch that all of this is accomplished by the single operation on the part of a cook, it

is an extremely easy matter to convert a coal operated stove into a gas operated range, both of which have one oven highly efficient for cooking purposes.

5 The above are by no means all the leading features or characteristics of my invention, but have been simply pointed out to impart some idea as to what I have accomplished by this invention, which will be hereinafter 10 described and then claimed, and reference will now be had to the drawings wherein—

Figure 1 is a plan of the combination coal and gas range;

Fig. 2 is a side elevation of the same, 15 partly broken away and partly in section, showing the operation of the range with gas and coal;

Fig. 3 is an end view of the stove, partly broken away and partly in section, showing 20 the stove under gas operation;

Fig. 4 is a similar view showing a portion of the stove under coal operation;

Fig. 5 is a rear elevation of an air and gas mixing device adapted to form part of the 25 stove;

Fig. 6 is a side elevation of the same;

Fig. 7 is a plan of the stove, partly broken away and in horizontal section, taken on the line VII—VII of Fig. 2; and

30 Fig. 8 is a similar view taken on the line VIII—VIII of Fig. 2.

A combination coal and gas range in accordance with my invention comprises a base 1 and on this base is a structure having 35 end walls 2 and 3, a rear wall 4, a front wall 5, and a top wall 6. The front and rear walls, adjacent the end wall 3 and the top wall 6 are connected by vertical and horizontal partitions 7 and 8, the vertical partition 7 coöperating with the end of the structure in providing a fire place, including a 40 grate 9, and such other appurtenances as are necessary for solid fuel.

The rear wall 4 has an offset portion or 45 flue casing 10 provided with a connection 11 for a stove pipe (not shown).

The space between the horizontal partition 8 and the top wall 6 of the stove structure constitutes a horizontal flue 12 and this 50 flue is adapted to communicate with the flue casing 10 by an opening 13 having a conventional form of damper 14 that may be adjusted to regulate the draft of the coal stove.

Connecting the front and rear walls of 55 the stove structure is an oven shell comprising an oven bottom 15 and side walls 16 and 17. The side wall 17 is in spaced relation to the end wall 2, thereby providing a vertical flue 18 which has the upper end thereof in 60 communication with the horizontal flue 12 and the lower end of the vertical flue 18 is in communication with a bottom horizontal flue 19 between the oven bottom 15 and the base 1. The side wall 17 therefore meets 65 the oven bottom 15, as best shown in Fig. 2

and the upper edge of the side wall 17 terminates at an inclined transverse portion 20 of the horizontal partition 8. The side wall 16 is in spaced relation to the vertical partition 7, thereby providing a vertical flue 70 21 at that side of the oven adjacent the coal stove. The upper edge of the side wall 16 is curved inwardly in spaced relation to the horizontal partition 8, so that the upper end of the flue 21 may communicate with the upper portion of the oven. The side wall 16, above the oven bottom 15 has a transverse opening 22 and the lower end or edge of the side wall 16 terminates in an angularly disposed portion 23 having slots 24 and 25. 80 Joining the angularly disposed portion 23 and the base 1 is a transverse angularly disposed brace or partition 26, said partition joining the angularly disposed portion 23 between the slots 24 and 25, so that the slot 85 25 will communicate with the bottom horizontal flue 19 and the slot 24 communicating with the atmosphere through the medium of openings 27 in the base 1.

One end of the bottom horizontal flue 19 90 is formed by the lower edge of the side wall 16 and by the brace or partition 26, while the other end of the flue is formed by the end wall 2 of the stove structure. In this horizontal flue is a central longitudinal vertical partition 28 extending from the end wall 2 and assisting in supporting the oven bottom 15. The partition 28 terminates about 95 centrally of the oven bottom, as best shown in Fig. 8, thereby dividing the bottom horizontal flue 19 into two parallel communicating passages for purposes which will herein-after appear.

Pivoted in the walls 17 and 2 and extending transversely of the vertical flue 18 is a 105 stove bolt 29 having the outer ends thereof provided with a crank 30. Fixed on the stove bolt 29, within the vertical flue 18, is a deflector comprising angularly disposed wings 31 and 32, said wings being at an obtuse angle and adapted to be adjusted by partial rotation or rocking movement of the stove bolt 29. The wings 31 and 32 correspond in width to the vertical flue 18 and the wing 31 is adapted to engage an angularly disposed ledge 33 carried by the rear wall 4 of the stove structure and this rear wall has a large opening establishing communication between the vertical flue and the flue casing. That edge of the wing 31 contiguous to the end wall 2 of the stove structure has a shutter 34 adapted to close an opening 35 in the end wall 2, when the wing 31 is in engagement with the ledge 33. 115

The wing 32 of the deflector is adapted to 120 engage the vertical partition 28, as best shown in Fig. 4, and that edge of the wing adjacent the oven side wall 17 has a shutter 36 adapted to close an opening 37 in the lower edge of the side wall 17. 130

Adjustable on the angularly disposed portion 23 of the side wall 16 is a burner damper 38 having a slot 39 adapted to register with the slot 24, and said damper is adapted to 5 close the slot 25. The damper 38 is supported on the angularly disposed portion of the wall 16 by pins 40 extending into angularly disposed slots adjacent the ends of the damper, and one end of the damper extends 10 through the rear wall 4 of the oven and has an apertured ear 42.

Extending through the rear wall 4 and parallel with the upper edge of the burner damper 38 is a burner 43 provided with a row 15 or series of openings directed toward the flue 21 and a series of openings directed toward the slot 25 in the lower inclined portion of the wall 16, so that flames can be maintained in the flues 21 and 19. The inner end of the burner 43 is closed and the outer end thereof is provided with an air and gas mixing device 44, preferably of that type disclosed in 20 Patent No. 1,144,501, granted June 29, 1915, to C. R. Pomaville. This air and gas mixing device is best shown in Figs. 5 and 6 as 25 having a shutter 45 adjustable simultaneously with a gas valve 46 having a jet extending into the air and gas mixing device. The plug or stem 47 of the valve 46 has an 30 arm 48 adapted for adjusting the shutter 45 and fitted over the end of the plug or stem 47 is a rod 49 parallel with the rear wall 4 and supported by a bracket or hanger 50 carried by said wall. The rod 49 adjacent the 35 valve 46, has a hook shaped member 51 and loosely connected to said member and the apertured ear 42 of the burner damper 38 is a link 52 which permits of the valve 46, the device 44 and the damper 38 being simultaneously adjusted by rocking or rotating of 40 the rod 49.

At the outer end of the rod 49 is a crank 53 and loosely connected thereto is an adjustable member or slide bar 54 parallel 45 with the end wall 2 of the stove structure. The adjustable member 54 is supported in a strap or bracket 55 connected to the wall 2 and said member has a slotted portion 56 to receive the crank 30 of the flue deflector. A 50 handle 57 on the outer end of the member 54 permits of said member being shifted so that the cranks 30 and 53 may be moved. An enlarged portion 58 on the lower edge 55 of the member 54 is adapted to have one of its ends abut either side of the strap 54 and thus determine the position of the member 54 for different adjustments.

The valve 46 is supplied with gas or other fuel by a pipe that extends longitudinally 60 back of the stove structure and then upwardly by a pipe 59 to a T connection 60 which accommodates a gas or fuel supply pipe 61 and a pipe 62 that extends forwardly and in front of a grid casing or compartment 65 63 in the top of the stove structure, as

best shown in Figs. 1 and 2. The grid casing 63 has grids 64 and contains burners 65 supplied with gas or fuel from the pipe 62. Ordinary gas and air mixing devices 66 and valves 67 control and regulate the operation of the burners 65, which are preferably of that type disclosed in my Patent No. 1,256,243, granted Feb. 12, 1918. 70

When it is desired to use gas as a fuel for cooking purposes, the oven door is opened, 75 the adjustable member 54 pulled outwardly to the position shown in Fig. 3, and then the gas ignited at the burner 43. This may be accomplished as the burner 43 is adjacent the opening 22 in the oven wall 16. The oven 80 door may be closed and to bake or otherwise cook anything in the oven, it may be safely placed upon the oven bottom 15 or upon grids or frames adapted to be supported by the walls 16 and 17. During the operation 85 of the oven, under gas, the damper 38 is set, as shown in Fig. 2, so that the lower part of the flue 21 receives air and this air, together with the products of combustion can circulate about the oven, as indicated by arrows 90 in Fig. 2. The heated air will also pass through the opening 37 in the oven wall 17 and into the horizontal bottom flue 19 to the vertical flue 18 from where it passes into the flue casing 10 and the stovepipe connected 95 thereto.

When the adjustable member 54 was pulled outwardly five adjustments were simultaneously made, namely, the gas was turned on at the valve 46, the burner damper 100 38 was adjusted, also the shutter 45 of the air and gas mixing device 44, the flue deflector was shifted so that the opening 35 was uncovered, also the opening 37 of the oven wall 17. With the opening 35 uncovered, air may enter the opening and induce a draft through the vertical flue 18 toward the casing 10, and by reference to Fig. 3, it will be noted that the flue deflector has the ends of its wings in spaced relation to the 110 front and rear walls of the stove structure and when in such position constitutes practically a horizontally baffle in the lower part of the flue 18, causing the heated air and products of combustion to travel toward the 115 ends of the wings 31 and 32 in order to escape into the flue casing. This insures thorough heating of the oven wall 17 and serves to sufficiently retard the heated air and products of combustion so that all of the 120 walls of the oven, particularly the oven bottom will be heated.

During the operation of the stove with gas, the gas may be regulated by slightly shifting the adjustable member 54 and there 125 is sufficient play at the link 52 to permit of a slight rocking or rotative movement of the rod 49 without affecting the position of the damper 38. When the gas is regulated, for instance lowered, of course the flue deflector 130

is shifted, but the opening 37 is still uncovered while the area of the opening 35 is slightly reduced, consequently the draft is not so strong toward the flue casing. This 5 has been worked out to a nicety so that there is proper oven ventilation and a circulation of heat which insures a uniform heat throughout the oven.

To discontinue the use of gas, the adjustable member 54 is pushed inwardly to the position shown in Fig. 4, and this operation places the stove structure in condition for the use of coal or other solid fuel should it be desired to use the same. With the member 15 54 pushed inwardly, the shutter 36 of the flue deflector closes the opening 37 and the shutter 34 closes the opening 35. The wing 31 now engages the ledge 33 and the wing 32 engages the partition 28 in the 20 horizontal bottom flue 19. The member 38 has closed the slot 24 and also the slot 25, and with the damper 14 closed, the products of combustion from the coal fire must pass over the top of the oven through the flue 25 12, and then downwardly in the vertical flue 18 as shown by arrows in Fig. 4. The products of combustion will impinge against the wing 31 of the flue deflector and enter the front passage in the horizontal bottom flue 30 19. From this passage the products of combustion travel around the end of the partition 28 into the rear passage of the flue and upwardly in the vertical flue 18, beneath the wing 31 into the flue casing 10. In this 35 instance, the flue 21 within the oven is placed out of commission, as the oven is sealed against any of the products of combustion entering the same, but all of the oven walls will be thoroughly heated before the escape 40 of the products of combustion.

From the foregoing it will be observed that the five adjustments made through the medium of the member 54 are very essential in order that a coal stove can be converted 45 into a gas range, and that the problem has been solved by the location of the burner 43 and the combined flue deflector and baffle, as otherwise it would be practically impossible to properly heat the oven bottom 50 by gas or coal.

In operation with either gas or coal, the burners 65 may be employed for cooking purposes and the damper 14 may be adjusted to increase or decrease the draft for 55 coal.

What I claim is:—

1. The combination of an oven having communicating flues adapted to communicate with said oven and different sources of 60 heat, means in one of said flues serving as a baffle when wholly therein and adapted to be adjusted to extend into another flue and cause heat from one source to travel in said flues in a different way from the heat 65 of the other source, and means reciprocable

at the end of the oven for actuating the first mentioned means.

2. In an oven structure adapted to be heated by coal and gas, an oven with flues thereabout, and one of said flues adapted 70 to communicate with said oven through an end wall thereof and with the atmosphere through an end wall of the stove structure, a partition in the flue below said oven, and an adjustable member in said flue which in 75 one position cooperates with said partition in deflecting coal products under said oven and around said partition, and in another position baffles gas products.

3. A stove structure as characterized in 80 claim 2 in which adjustment of said member controls the operation of the stove by gas.

4. A stove structure as characterized in 85 claim 2, in which the adjustable member is actuated by a crank and a slide bar at the end of the stove structure.

5. In a combination coal and gas range, a stove structure having an oven with flues thereabout, a fire place in said structure 90 communicating with said flues, a gas burner adapted to communicate with said oven and said flues, a valve controlling the operation of said burner, an air and gas mixer for said burner, a damper adapted to admit air about 95 said burner, a deflector in an end flue of said range, and a member reciprocable at one end wall of said range adapted to simultaneously adjust said valve, mixer, damper and deflector.

6. In a combination coal and gas range, a stove structure having an oven with flues thereabout, a fire place in said structure communicating with said flues, a gas burner adapted to communicate with said oven and said flues, a valve controlling the operation of said burner, an air and gas mixer for said burner, a damper adapted to admit air about said burner and control its communication with one of said flues, a deflector in one of said flues, shutters carried by said deflector controlling communication between said oven and one of said flues and the same flue and the atmosphere, and means adapted to simultaneously adjust said valve, 115 mixer, damper and deflector.

7. In a stove structure, a walled oven with flues thereabout said oven having a slotted wall projecting from the bottom thereof at one end of said oven and adapted to separate two of said flues, a damper slidable on the slotted portion of said wall, a stationary burner in the plane of the oven bottom adjacent said damper adapted to direct flames into the said two flues when said damper is 120 in an open position, a valve controlling the operation of said burner, and means adapted for simultaneously operating said valve and said damper.

8. A stove structure as characterized in 130

claim 7, in which said means includes a loose link connection so that said valve may be regulated between extreme open and shut positions without affecting said damper.

5 9. A stove comprising a base; end walls; a front wall; a rear wall; a top wall; vertical and horizontal partitions coöoperating with an end wall, front, rear and top wall in providing a coal fire place and a flue 10 therefor; an oven bottom between said front and rear walls coöoperating with said base in forming a bottom flue; a longitudinal partition in said bottom flue extending from one of the end walls of said stove and assisting 15 in supporting the oven bottom; side oven walls between said front and rear walls with one of said side walls extending to said base and both of said side walls coöoperating

with aforementioned walls and partitions in providing vertical flues; a gas burner in one 20 of said vertical flues; a valve controlling the operation of said burner; a deflector in the other of said vertical flues, and means adapted for simultaneously adjusting said valve and deflector.

25 10. A stove structure as characterized in claim 9, in which a slidable damper is located below said burner for rendering one of said vertical flues inactive during the use of said fire place.

30 In testimony whereof I affix my signature in the presence of two witnesses.
